US00D999082S

(12) **United States Design Patent** (10) **Patent No.:** **US D999,082 S**
(45) **Date of Patent:** **** Sep. 19, 2023**

(54) **CUFF FOR WATCH**

(71) Applicant: **STEEL AMERICAN LUXURY LLC**,
Winnetka, IL (US)

(72) Inventor: **Nicole Steel**, Winnetka, IL (US)

(73) Assignee: **STEEL American Luxury LLC**,
Winnetka, IL (US)

(**) Term: **15 Years**

(21) Appl. No.: **35/003,020**

(22) Filed: **Mar. 29, 2022**

(80) **Hague Agreement Data**

Int. Filing Date: **Mar. 29, 2022**

Int. Reg. No.: **DM/220616**

Int. Reg. Date: **Mar. 29, 2022**

Int. Reg. Pub. Date: **May 13, 2022**

(57) **CLAIM**

The ornamental design for a cuff for watch, as shown and described.

DESCRIPTION

1. Cuff for watch

1.1 : Perspective

1.2 : Bottom Perspective

1.3 : Front

1.4 : Back

1.5 : Right

1.6 : Left

1.7 : Top

1.8 : Bottom

The figures include surface shading, which represents contour and not surface ornamentation; the broken lines in the figures illustrate features or environment which form no part of the claimed design.

1 Claim, 8 Drawing Sheets
